UNITED STATES PATENT OFFICE.

NUMA BÉGUELIN, OF SOLOTHURN, SWITZERLAND.

STEM-WINDING MECHANISM.

No. 819,714.

Specification of Letters Patent.

Entered May 8, 1906.

Application filed September 16, 1904. Serial No. 224,705.

To all whom it may concern:

Be it known that I, NUMA BÉGUELIN, a citizen of the Republic of Switzerland, residing at Solothurn, Switzerland, have invented 5 certain new and useful Improvements in Stem-Winding Mechanism, of which the following is a specification.

This invention relates to a keyless mechanism for winding up and setting the hands 10 of watches, whereby according as the winder-stem is pushed more or less inward the hands will be set or the going-spring wound up.

A construction of the mechanism according 15 to this invention is illustrated, by way of example, in the accompanying drawings, in which—

Figure 1 is a plan view, the parts being shown in the position for the winding of the watch. Fig. 2 is a plan view with the parts 20 in the position for setting the hands. Fig. 3 is an under side view, partly in section, of the mechanism opposite to that of Fig. 1.

The winding-sleeve A, operated by a pendant-stem A', provided with a turn-button or 25 knob A², has loosely mounted upon it a crown-wheel with peripheral teeth B and lateral teeth B'. The lower square portion A⁴ of the said sleeve A carries a longitudinally-sliding ratchet-clutch C, which can be made by the 30 action of a lever D, pivoted at d, either to engage with the wheel E for setting the hands or to become coupled to the teeth B' of the crown-wheel of the winding-gear. The sleeve A is provided throughout the whole of its 35 length with a central passage A³, in which can move a pin F, provided at the bottom with a head G, which is constantly pressed upon by a lever K, pivoted at K³, mounted between the plate L and a pillar-plate. In 40 the plate L are guide-grooves L' L², through which project pins K' K² on the lever K. These pins engage, respectively, a clutch-operating lever D, pivoted at d, and a strong spring P, normally tending to force the pin K² inward and the pin K' against the side of the pivoted lever D. (See Fig. 2.) A second spring N is provided to act against the tail of the lever D to cause it when the parts are in the position shown in Fig. 1 to move the clutch C into engagement with the lateral teeth B' of the crown-wheel B, Fig. 1.

The operation is as follows: In the position shown in Fig. 2 the spring P acts against the pin K², pressing it inward, thereby causing the arm K⁴ of the lever K to press against the headed pin F. The other pin K' is at the

same time pressed against the lever D, causing the clutch C to engage the pinion E for setting the hands. Now when the pin A' is pressed inward by its knob A² the pin F is 60 also moved inward, pressing away the end K⁴ of the lever K against the action of the spring P, which, together with the pins K' and K², is pressed back into the position 65 shown in Fig. 1. The forward end of the lever D is consequently freed from the pressure of the pin K², and the spring N can thereupon act upon the tail of the lever D to cause it to slide the clutch member C into engagement with the lateral teeth B' of the 70 crown-wheel for the purpose of winding up the watch. A screw at the side of the plate L has half of its head cut away, as shown, Figs. 1 and 2, to enable the spring P to be released when fitting up before putting the 75 mechanism into the casing, while by turning the head through a half or quarter revolution the head of the screw will form a seating for the end of the spring and put it into operative position.

The winding and setting pin can be secured from complete withdrawal from the watch-casing in any usual or suitable manner.

What I claim as my invention, and desire to secure by Letters Patent, is—

1. In a watch-hand setting and winding mechanism, a pivoted lever, two pins thereon, a pivoted clutch-operating lever situated between the pins, and a spring acting on one pin, and a second spring acting against the 90 tail of the clutch-operating lever, substantially as set forth.

2. In a watch-hand setting and winding mechanism comprising a longitudinally-movable winding and setting pin, a rotatable 95 sleeve, a crown-pinion loosely mounted on said sleeve, a double clutch longitudinally movable on said sleeve, a pivoted lever operated by the winding and setting pin, two pins on said lever, a strong spring acting 100 against one pin, a pivoted clutch-operating lever and a second spring acting against the tail of said lever in opposition to the first-named spring substantially as set forth.

3. A watch-hand setting and winding 105 mechanism comprising a hollow sleeve A, a winding and setting pin A', a pin F, a crown-pinion B, a longitudinally-movable clutch C, a lever K, pins K' K² thereon, a pivoted lever D and springs P, N, substantially as set forth.

4. In a watch-hand setting and winding mechanism the combination of a rotatable

hollow sleeve of part circular and part angular bore, a winding and setting pin adapted to engage and move longitudinally in the angular portion of the bore, a pin longitudinally movable in the circular bore of the sleeve, a head on the bottom end of the pin, a crown-pinion loosely mounted on the sleeve, a double clutch longitudinally movable on said sleeve, a pivoted lever operated by the winding and setting pin, two pins on said lever, a strong spring acting against one pin, a piv-

oted clutch-operating lever and a second spring acting against the tail of said lever in opposition to the first-named spring substantially as set forth. ¹⁵

In testimony whereof I have signed my name to this specification in the presence of two subscribing witnesses.

NUMA BÉGUELIN.
